BRASSIERE

Pierre Amyot, Sillery, Quebec, Canada, assignor to Sa-
rong, Inc., West Haven, Conn., a corporation of Con-
necticut

Application May 1, 1957, Serial No. 656,350

4 Claims. (Cl. 128—483)

The invention relates to a brassiere in which a novel construction of the breast pockets thereof produces a garment in which independent adjustment of each breast pocket, to accommodate variations in the bust size of the wearer of the garment is automatically secured, and which adjustment effects the necessary separation of the breasts and yet yields a proper and healthful support for the bust and proper molding thereof.

The desired effect is produced primarily by my novel construction of brassiere in which the breast pockets are free of attachment to one another and in which each breast pocket is secured to one of a pair of freely crossed diaphragm bands arranged below the breast pockets in such manner as to produce a perfect control of the fit of the garment for comfort, support, stability, and freedom of movement of the wearer. By the utilization of such freely crossed diaphragm bands and breast pockets which are free of attachment to one another, the proper molding of the bust is secured, irrespective of the wearer's bust measurements and the requirement of a particular size of garment by reason thereof, and irrespective of the bodily movements of the wearer during normal activity.

In accordance with my invention, I provide a brassiere having two completely independent breast pockets, free of attachment to one another, and differing substantially from brassieres of prior construction in that the breast pockets or cups are not sewn to each other at the center of the garment, nor to a transverse section conventionally provided between such cups, but in which one breast pocket or cup is attached to the opposite side panel of the garment and is entirely free to move independently of the adjacent breast pocket or cup.

The primary object of my invention is to provide a novel brassiere construction in which the breast pockets are free of attachment to one another and are independently adjustable to accommodate, and properly fit, support, and mold the breasts of the wearer of the garment by the securing of each of such breast pockets to one of a pair of freely crossed diaphragm bands extending below and across the breast pockets.

Other objects and features of my novel construction of brassiere, for instance, the greater length of one of such freely crossed diaphragm bands than the length of the second of such bands, for improved and proper fitting of the garment, and the particular configuration of such bands for further inducing the desired separation of the bust, will be apparent from the following description of a specific embodiment of my novel construction of brassiere illustrated in the accompanying drawing, in which:

Fig. 1 is a front view in elevation of a brassiere embodying this invention;

Fig. 2 is a fragmentary rear view of the central portion of said brassiere;

Figs. 3 and 4 are detail views of the separate diaphragm bands shown in Figs. 1 and 2.

Referring more particularly to the drawings, the brassiere comprises a pair of breast pockets 5 and 6 attached along their outer side edges as indicated at 7 and 8 respec-

2

tively, to the upper portion of the front edges of body encircling side panels 9 and 10. Side panels 9 and 10 are provided at their free rear ends with suitable complementary fastening elements for securing the brassiere about the wearer. Referring to the pocket 5, e.g., the desired cup shape and fullness may be obtained by pre-forming it of two pieces 11 and 12.

The breast pocket 5 is attached along its lower edge to a diaphragm band generally indicated at 13. Similarly 10 breast pocket 6 is attached along its lower edge to a second diaphragm band 14. A triangular breast contour moulding band 15 of flexible material is secured along its inner side 16 to the inner edge of breast pocket 5 and along its lower sides 17 and 18 which form a triangular 15 extension into a V-shaped notch cut in the upper central section of diaphragm band 13. A second triangular breast contour moulding band 19 of flexible material is secured along its inner side 20 to the inner edge of breast pocket 6 and along its lower sides, similarly forming a triangular extension into a V-shaped notch cut into the upper central section of diaphragm band 14.

As will be seen in Figs. 3 and 4, the diaphragm bands 13 and 14 are separately formed from a flexible fabric, which may be single or double ply. Diaphragm band 13 has its upper edge shaped to provide a concave outline 21 extending from the left side edge 22 to one side of a deeply notched central section 23 and a second concave outline 24 extending from the other side of the deeply notched central section 23 to the right side edge 25, which is provided with a triangular elastic tab 26. Both the left and right side edges 22 and 25, the latter through tab 26, are downwardly and inwardly inclined to meet a lower edge 27 which is inclined upwardly from right to left resulting in the side edge 25, including its tab 26, being of a substantially greater length than the side edge 22. Additionally, the length of the upper concave outline 21 is preferably slightly greater than the length of the upper concave outline 24.

The deeply notched central section 23 is further cut 40 with a slit 28 for securing a proper meeting of the elastic bands hereinafter described with the material of the notched central section 24.

The dimensions of the diaphragm band 14 are substantially identical with those of diaphragm band 13 but the band 14 is disposed in inverse relation to band 13 so that concave outline 29 corresponding to outline 21 is at the right of a deeply notched central section 30 and concave outline 31 corresponding to outline 24 is at the left of the deeply notched central section 30. Similarly, 50 the short side edge 31 is on the right and the longer side edge 32, with a corresponding triangular elastic tab 33 is on the left and therefore the lower edge 34 inclines upwardly from left to right. The deeply notched central section 30 of band 14 is similarly provided with a slit 35.

55 The diaphragm band 13 has its short side edge 22 secured along the lower portion of the front edge of side panel 9 a substantial distance above the lower edge of said side panel. The concave outline portion 21 is secured along the lower edge of breast pocket 5, and the 60 notched central section 23 has sewed thereinto the lower extremity of the elastic triangular breast moulding band 15, which lower extremity is formed to fit into the deeply notched central section 23 of the diaphragm band. The concave outline portion 24 extends freely along a contour lying within and substantially, but not quite concentric with the contour of the lower edge of breast pocket 6. The elongated side edge 25 and its tab 26 are secured along the lower portion of the front edge of side panel 10 from the base of the side panel up to the 65 point of merger of the lower edge of said breast pocket 6 with the said side panel.

The diaphragm band 14 has its short side edge 31

secured along the lower portion of the front edge of side panel 10 a substantial distance above the lower edge of side panel 10 and in lapping relation with a complementary secured portion of the side edge 25 and tab 26 of band 13. The concave outline portion 29 of band 14 is secured along the lower edge of breast pocket 6 and the notched central section 30 has sewed thereto the lower extremity of the second elastic moulding band 19. The concave outline portion 36 extends freely along a contour lying within and substantially, but not quite concentric with the contour of the lower edge of breast pocket 6. The elongated side edge 32 and its tab 33 are secured in lapping relation with the side edge 22 of band 13 along the lower portion of the front edge of side panel 9 from the base of the side panel up to the point of merging of the lower edge of said breast pocket 5 with said side panel.

As will be seen in Figs. 1 and 2, the diaphragm bands 13 and 14 are arranged in criss-cross relation and are free of direct attachment to each other except at their common points of attachment to the front edges of side panels 9 and 10. Additionally, the breast pockets 5 and 6 and their respective contour moulding bands 15 and 19 are free of attachment to each other. Thus there is a freedom of movement of breast pocket 5 and its corresponding diaphragm band 13 relative to the breast pocket 6 and its corresponding diaphragm band 14 and vice versa. Also, the contour moulding band 15 attached to breast pocket 5 and diaphragm band 13 functions independently of the contour moulding band 19. Similarly, contour moulding band 19 attached to breast pocket 6 and diaphragm band 14 functions independently of the contour moulding band 15.

This independent action of the right and left band breast pockets and their component elements allows for a variation in the bust width of different people. The term bust width is employed to designate the distance between the two breasts of a person, center to center. In this connection, it is pointed out that the bust width varies from one person to another although their circumferential measurement about the body at the bust line is substantially the same. Thus, if several women have a body circumferential measurement at the bust line of 32 to 34 inches, they will all normally require a size 32-34 brassiere. However, their bust width, from center to center of the breasts, will vary in some cases. With the conventional brassiere in which the inner edges of the pockets are either directly connected or are connected to a common central panel, there is no provision or at least no adequate provision for independent adjustment of each breast within the corresponding pocket of the brassiere. The reason for this is that, for example, lateral adjustment of one breast pocket makes a corresponding lateral adjustment of the other. Thus, if outward lateral adjustment is required it must be made relative to the breast pocket centers resulting in discomfort to the wearer. On the other hand, if the required adjustment is not made, there will be an improper fitting and support with resulting discomfort.

The separation feature of the present invention solves the above problems by correctly accommodating all variations in the bust width within at least a standard range. This new feature of variable bust separation is obviously a marked improvement over the above mentioned conventional brassieres in that it provides a freedom of movement not heretofore experienced and makes the brassiere much more stable on the body.

Another feature resides in the combination of the triangular breast contour moulding bands arranged in free criss-cross relation to each other along the inner side of each breast pocket and the separate diaphragm bands similarly arranged in free criss-cross relation to each other so that, while each diaphragm band permits independent adjustment of the breast within the corresponding pocket, the contour moulding band exerts a

moulding pressure along the inner side of the breast which is properly adjusted in the corresponding pocket and independently of the moulding pressure applied by the other breast moulding band. This combination materially contributes to the control of the fit of the brassiere as regards comfort, stability and freedom of movement for any wearer of the garment notwithstanding the fact that there is a variation in the bust width of different wearers of brassieres of the same size.

The securing of the moulding bands 15 and 19 in the deeply notched central section of each diaphragm band contributes, in great measure to the spreading of the bust sections and the separation of the bust from center to center of the breasts.

In addition to the free criss-cross arrangement of the diaphragm bands, other features that contribute to the freedom of independent adjustments are (1) the attachment to the side panel of that portion of each diaphragm band which is attached to the corresponding pocket is of relatively narrow width as compared with the relatively broad attachment of the other portion to the opposite side panel, (2) the central support of each diaphragm band from the lower end of the corresponding breast contour moulding band, and (3) the concave curve of the upper free edge of that portion of each diaphragm band which extends across the opposing breast pocket section to reduce the effect of any movement of said band on the opposite breast pocket section to a minimum.

It will be noted that while the two diaphragm bands 13 and 14, when laid out flat, as shown in Figs. 3 and 4, are substantially equal in length, when they are inserted into their proper positions below the breast cups, they are disposed in inverse relation to each other, the long concave side of each band being stitched to its respective bust section and the short concave side of each band being free of attachment to the bust section below which it is disposed. Thus, the two diaphragm bands form, at their central or median points, a cross-over structure that exhibits a sufficient ability to spread on each side of the brassiere center to accommodate and compensate for variation in bust separation.

I claim:

1. A brassiere embodying a pair of breast pockets adjacently arranged, and free of attachment to one another, a first side section having its front edge secured to the outer edge of a first one of said breast pockets, a second side section having its front edge secured to the outer edge of the second of said breast pockets, a pair of crossed diaphragm bands located below said breast pockets, each diaphragm band being wider at one end than at the other end, a first one of said diaphragm bands having its narrower end secured along a portion of the front edge of said first side section and the upper edge portion underlying said first breast pocket secured along the lower edge of said first breast pocket, the remaining upper edge portion of said first diaphragm band extending freely below said second breast pocket and having its wider end secured along a portion of the front edge of said first side section, the lower edges of said diaphragm bands extending across the bottom of the brassiere in a criss-cross angular arrangement from a point below one breast pocket to a point below the other breast pocket and from one side of the front of the garment to the other, and in which the narrower end of each of said diaphragm bands is secured to an adjacent side section directly below the correspondingly attached breast pocket and in which the wider end of each of said diaphragm bands is secured along an adjacent side section directly below a correspondingly attached breast pocket, a portion of each of said wider ends being in lapping relation to the narrower end of the other of said diaphragm bands.
2. A brassiere as set forth in claim 1 in which each of the wider end portions of said diaphragm bands comprises a triangular elastic tab.

3. A brassiere embodying a pair of breast pockets adjacently arranged, and free of attachment to one another, a first side section having its front edge secured to the outer edge of a first one of said breast pockets, a second side section having its front edge secured to the outer edge of the second of said breast pockets, a pair of crossed diaphragm bands located below said breast pockets, each diaphragm band being wider at one end than at the other end, a first one of said diaphragm bands having its narrower end secured along a portion of the front edge of 10 said first side section and the upper edge portion underlying said first breast pocket secured along the lower edge of said first breast pocket, the remaining upper edge portion of said first diaphragm band extending freely below said second breast pocket and having its wider end secured along a portion of the front edge of 15 said first side section, the lower edges of said diaphragm bands extending across the bottom of the brassiere in a criss-cross angular arrangement from a point below one breast pocket to a point below the other breast pocket and from one side of the front of the garment to the other, and in which the narrower end of each of said diaphragm bands is secured along an adjacent side section from a point adjacent the lower edge of the correspondingly attached breast pocket to a point substantially distant from the lower edge of the said side section and in which the wider end of each of said diaphragm bands is secured along an adjacent side section from a point adjacent the lower edge of the correspondingly attached breast pocket to the lower edge of the side section.

4. A brassiere embodying a pair of breast pockets adjacently arranged, and free of attachment to one another, a first side section having its front edge secured to the outer edge of a first one of said breast pockets, a second side section having its front edge secured to the outer edge of the second of said breast pockets, a pair of crossed diaphragm bands located below said breast pockets, each diaphragm band being wider at one end than at the other end, a first one of said diaphragm bands having its narrower end secured along a portion of the front edge of said first side section and the upper edge portion underlying said first breast pocket, the remaining upper

5
